SHARPENING DEVICE

John Gallo, Boston, Mass.

Application September 3, 1941, Serial No. 409,431

5 Claims. (Cl. 76—87)

This invention relates to sharpening implements and more particularly to devices for sharpening cutlery such as knives and related instruments.

Among the objects of the present invention is the provision of relatively simple sharpening devices and instruments for knives and related articles which enable adjustment of the sharpening elements with respect to each other.

Other and further objects of the invention will appear from the more detailed description set forth below, it being understood, however, that this more detailed description is given by way of illustration and explanation only, and not by way of limitation, since various changes therein may be made by those skilled in the art without departing from the scope and spirit of the present invention.

In accordance with that more detailed description, there is shown for exemplary purposes, in the accompanying drawings, in

Figure 1, a side elevation of a sharpening implement produced in accordance with the present invention; in

Figure 2, a section on the line 2—2 of Figure 1; in

Figure 3, a section through a modified form of sharpener produced in accordance with the present invention; in

Figure 4, a side elevation of a further modification produced in accordance with the present invention; in

Figure 5, a side elevation of a further modified form produced in accordance with the present invention; in

Figure 6, a top elevation partly in section of the form of device shown in Figure 5; in

Figure 7, a detail of the device of Figures 5 and 6; in

Figure 8, a further modified form of instrument produced in accordance with the present invention; in

Figure 9, a further modification of a device produced in accordance with the present invention; in

Figure 10, a still further modified form of device produced in accordance with the present invention; in

Figure 11, a form in which the adjustment means is at the handle end of the device; and in

Figure 12, a further modified form in which the adjustment means is at the handle end of the device.

In accordance with the present invention, sharpening implements are provided for knives

and related articles utilizing opposed sharpening elements between which the knife blade or similar instrument edge is drawn; most desirably the sharpening element taking the form of metallic discs and in the preferred instance such sharpening discs being co-planar and having peripheral contact. The sharpening elements are mounted so that the distance between the sharpening elements may be varied while at the same time means are provided for fixing the position of the discs with respect to each other so that during actual use, the maximum distance between the sharpening elements is fixed. By the provision of such means, the "bite" of the sharpening elements may be changed from time to time as desired while still insuring that the distance between the sharpening elements will be maintained at a fixed position during actual use.

Referring to the drawings, there is shown in Figure 1, one form of sharpening implement produced in accordance with the present invention. As illustrated, a body portion 1 of any desired cross-sectional contour has a handle portion 2 at one end thereof, rigidly held on the body member 1. At the end opposite from that carrying the handle portion 2, the body member is provided with a threaded extension 3 for reception of the base member 4. In this form of the device, the base member 4 is shown as composed of a body portion 5 which desirably may be made of plastic or any other desired material, having an internally threaded recess 6 enabling it to be applied to the threaded extension 3 of the body member 1; the body portion 5 desirably having a flexible covering such as 7 of rubber or any other desired material, so that the implement may be applied against any desired surface without any danger of marring the latter.

The sharpening elements may be of any desired type but as illustrated are preferably formed of metallic sharpening discs in the form of two opposed co-planar pairs mounted on opposite sides of the body member 1 intermediate between the handle portion 2 and the base portion 4. Thus, a hole or perforation 8 is formed in the body portion 1, through which a shaft 9 extends on which are mounted the discs 10, 10, the ends of the shaft being enlarged or swaged over to form means for holding the discs in position. An ordinary rivet may be used as the shaft 9, the head 11 and burr 12 serving to hold the sharpening discs 10, 10 in position. Desirably washers 13 are also provided. A second opening or perforation 14 is provided in the body member 1 at a distance from the first perforation 8.

so that the discs will have peripheral contact when urged toward each other by the tightening up of the base member 4 on the threaded extension 3. The perforation 14 is in the form of a longitudinal slot enabling the shaft 15 placed therein to be movable to vary the distance between the shafts 9 and 15. A pair of sharpening discs 16, 16, are mounted on the shaft 15 on opposite sides of the body member 1, and here again the shaft 15 may take the form of an ordinary rivet, the enlarged head 17 and burr 18 serving to hold the sharpening discs 16, 16 in position; washers 19 being provided.

The base member 4 on being tightened on the threaded extension 3 of the body member 1 serves to force the pairs of coacting sharpening discs into peripheral contact with each other, a washer 20 desirably being provided between the body portion 5 of the base member 4 and the sharpening discs 16, 16. By adjustment of the base member 4 on the threaded extension 3, the distance between the discs 16, 16 and 16, 16 respectively, may be varied while at the same time in any predetermined set position, the base member 4 prevents movement of the discs away from each other to an extent predetermined by the positioning of the base member 4.

In the form of device shown in Figures 3 and 4, the means for restricting the distance between the shafts carrying the sharpening discs takes the form of an element bearing directly against such movable shafts, and holding the latter in a predetermined position. As illustrated the body member 21 is provided at one end with an internally threaded hole or opening 23, for reception of the base member 24, the latter carrying a knurled head 25 having a rubber tire 26, the head 24 carrying a screw 27 for reception in the internally threaded hole 23, the extreme inner end 28 of the screw 27 being adapted to engage against the shaft carrying the movable sharpening discs. Thus, the fixed shaft 29 carried in a hole or perforation in body member 1 carries sharpening discs 30, 30 on opposite sides of the body member 21, held on the shaft or rivet 29 by means of the head 31 and burr 32, washers 33 being provided. The movable shaft 34 is placed in the elongated opening 35 and carries sharpening discs 36, 36, held in position by the head 37 and burr 38, washers 39 being provided. The opening 23 in the end of the body portion 21 is carried all the way through into the elongated opening 35 so that the screw 27 may be advanced in the hole 23 until its reduced end 28 engages against the shaft 34. It will thus be apparent that the positioning of the screw 27 will determine the maximum distance permissible between the shafts 29 and 34 and once that distance has been predetermined by the position of the screw 27, the maximum distance between the shafts 29 and 34 and consequently the coacting sharpening discs 30, 30 and 36, 36 respectively, will be fixed during use.

The modification shown in Figure 4 of the drawings is similar to that of Figure 3 except that the means for adjustment is modified so that a hammer headed element 40 is made integral with the screw 41 corresponding with the screw 27 of the device of Figure 3, the other elements of the structure of Figure 4 being substantially the same as those of Figure 3 and the adjustment being secured in an analogous way. The hammer headed base member 40 is readily gripped for adjustment and also because of its shape has utility in other directions.

In the form of invention shown in Figures 5 to

7, the body portion 51 carries an elongated looped handle portion 52 desirably integral with the body portion 51. The other end of the body portion 51 ends in a threaded extension 53 on which is placed the base portion 54 desirably made of a plastic body portion 55 carrying the rubber cover or cap 56. A shaft 58 which may be in the form of an ordinary rivet is carried in a hole or perforation in the body portion 51 and carries a pair of sharpening discs 60, placed on opposite sides of the body portion 51 and held in position on the shaft by the headed end 61 and burr 62, washers 63 being provided. The shaft 64 is carried in an elongated opening 65 in the body member 51 properly positioned with respect to the shaft 58 and the first mentioned sharpening disc. The shaft 64 carries a pair of sharpening discs 66 on opposite sides of the body member 51 held in position by means of the head 67 and burr 68, washers 69 being provided. In this case, the pressure exerted by tightening the base 54 on the threaded end 53 of body member 51 is desirably applied to the movable discs 66, 66, through a washer 70 having a recess 71 which recess is divided into a series of facets 72, desirably provided in opposite pairs within the recess 71 so that when the washer 70 is pressed against the discs 66, 66, the latter engage into a pair of opposite facets 72 within the recess 71 and the washer is locked in position and exerts pressure directly against the discs 66, 66.

In the utilization of a sharpening implement of the character shown in Figures 5 to 7, the same thing applies as has been set forth above in connection with the other forms of invention and particularly that illustrated in Figures 1 and 2, both of which use a base portion threaded on an externally threaded end of the body portion in order to restrict the movement of the movable disc from the fixed disc during use while at the same time permitting adjustment of the distance between the discs as desired.

In the modification shown in Figure 3, the structure is generally similar to that explained above in connection with the devices of Figures 3 and 4, in that the body member 21 has the internally threaded opening 23 into which the screw 37 is threaded, the inner end of which contacts against the shaft 34 of the movable discs 36, 36 in the same manner as explained above in connection with Figures 3 and 4. The movable discs 36, 36 are in co-planar peripheral contact with the discs 30, 30, the mounting of the pairs of sharpening discs 30, 30 and 36, 36 respectively, being identical with that described above in connection with the mounting of the same discs in the devices of Figures 3 and 4. The adjustment screw 37 which bears against the shaft 34 carrying the discs 36, 36 is provided at its outer end with means for placing the implement against a wall or table or similar object and maintaining it in position thereon by the use, for example, of the suction cup of the usual type 88, carried on the link 89 which is pivoted as shown at 90 on the end of the screw 37. Desirably to hold the suction cup 88 in the angular position with respect to the screw 37 and the implement itself, washers 91, 91 are provided carried on the screw 37 with the interposed coil spring 92 about the screw 37 between the washers 91, 91. The coil spring 92 forces the outer washer 91 against the link 89 and holds the suction cup in desired angular position, any one of three fixed positions being possible depending on whether the washer 91 engages against the face

93 or the face 94 or the face 95 of the link 89. In the full line position indicated in Figure 8 a right angular relation is indicated between the suction cup 88 and the screw 87 and implements by the washer 91 bearing against face 93 of the link 89. In the dotted position indicated in Figure 8, the suction cup 88 is at an angle of 180° with the screw 87 and maintained in that position by the washer 91 engaging against the face 94 of the link 89. In this way any desired fixed position may be obtained in three predetermined arrangements to hold the suction cup in desired position so that the implements may be securely attached to a desired article for use of the implement for sharpening purposes. In other respects the sharpening device is utilized in the same manner as for the devices illustrated in Figures 3 and 4.

In the modification shown in Figure 9 a form of device generally similar to that illustrated in Figures 1 and 2 is employed in that the body member 1 is provided with coating pairs of co-planar peripherally contacting sharpening discs 10 and 16 mounted in the same way as the discs 10 and 16 of Figures 1 and 2 on the body portion 1. The adjusting means include the threaded extension 3 carried on the end of the body member 1. A wing nut 101 is threaded upon the threaded extension 3 and engages against the washer 102, arcuate in cross-section which bears against the adjustable disc 16. The tightening of the wing nut 101 on the threaded extension 3 forces the shoe 102 into contact with the disc 16 and provides for the adjustment of distance between the discs 10 and 16 while at the same time restricting the maximum movement possible of the discs 16 from the discs 10 during actual use. In order to support the device as shown in this modification, a block 103 is loosely mounted on the bolt 104 rigidly attached to the extension 3 of the body member 1. The block 103 is mounted so that it will turn freely on the bolt 104 and the block 103 carries the eye 105 which may be engaged with a nail or hook on a wall, for example, so that the sharpening implement may be held in that desired position during use. In utilization for sharpening purposes, the device is used in the same manner as in connection with the form of devices shown in Figures 1, 2 and 5-7.

In the modification shown in Figure 10, the internally threaded type is again employed substantially analogous to that explained above in connection with Figures 3 and 4, the screw 110 having an outer hook portion 111 engaging on its inner end with the internal threaded portion of the extension 112 of the body member 21 and engaging against the shaft on which the movable discs 36, 38 are mounted, enabling their positioning as desired with respect to the other set of coating, co-planar, peripherally contacting discs 38, 36, but restricting the maximum movement possible between the shafts, all as explained above in connection with the form of devices shown in Figures 3 and 4. The hook member 111 enables the device to be mounted or held in position for use on a nail, hook or other device held in a wall or similar structure.

The forms of devices illustrated in Figures 1-10 of the drawings show implements in which the adjustment means are operated from the base end of the device. Other arrangements are within the purview of the invention and as illustrated in Figures 11 and 12, the adjustment may be made from the handle end of the device.

Thus as shown in Figure 11, the body portion 121 is provided at one end with handle 122 threaded on the threaded extension 123 of the body portion 121. A base member 124 in form, for example, of a rubber ring is carried on the reduced portion 125 of body portion 121 and held in position by the head 126 which may be formed by swaging over the end of the reduced portion 125, a washer 127 being desirably used. A wing nut 128 threaded on the threaded extension 123 may be used for purposes hereinafter set forth.

The sharpening discs 129, and 130 are mounted in the same way as for the other forms of devices described above except that in this instance the hole 131 is used on the handle side of the sharpening discs, an enlarged hole being illustrated in lieu of the slot 14 of Figure 2. Enlarged holes or slots may be used as desired, the shape of the opening being immaterial so long as longitudinal movement of the shaft 132 carrying discs 130 is possible to and from the shaft carrying discs 129.

In this form of device the distance between the sharpening discs may be varied but the maximum distance is predetermined from the handle end. While the handle 122 may be tightened on the threaded projection 123 against the discs 130 to limit the position of the latter, more desirably the wing nut 128 is used for that purpose, a sufficient length of threaded projection 123 being provided for that purpose.

Figure 12 also shows a form of device generally similar to that of Figure 11 in that the threaded extension 143 on the handle end of the body portion 141 carries the handle 142 and wing nut 148 for limiting the movement of the sharpening discs 149 and 150 with respect to each other, the sharpening discs being mounted on the body member 141 similarly to that of any of the previously described devices.

In the form shown in Figure 12, the threaded extension 143 is square in cross-section, the longitudinal edges of the extension being cut to form the threads as shown at 151. In addition 45 the body portion 141 is provided at the end 152 opposite to that of the handle with an opening 153 for reception of the shank 154 of the eye 155. The eye 155 may be held in position in any desired way. As shown, the inner end of the shank 154 is enlarged as shown at 156 and such enlargement may be formed by punching the shank flat, which operation may be carried out through the transverse hole 157 in the body portion 141. In other respects the device of Figure 55 12 is similar to that of Figure 11.

The devices of the present invention supply sharpening implements for knives and related devices that are readily manufactured at relatively economical cost. Hardened steel discs are desirably employed for the sharpening discs but other forms of sharpening discs may be employed if desired. A double or two-way knife sharpener is readily produced in accordance with the present invention which is quite strong and of low expense. Desirably in using the sharpeners they are held in such a position that the knife, for example, is drawn across the sharpening discs, the knife being held in a substantially horizontal position while the sharpening discs are held at an angle of 45°. The sharpener may be reversed and the other pair of sharpening discs employed for a finishing cut or by loosening the base portions and similar elements, turning the discs 70 somewhat, and then tightening again a new bite 75

is obtained. The distance between the discs is predetermined as indicated above for any particular operation.

Having thus set forth my invention, I claim:

1. A tool for sharpening knives and related instruments which comprises a body member having a threaded end, a shaft carried on said body member, a sharpening disc mounted on said shaft, a second shaft carried on said body member movably positioned with respect to the said first mentioned shaft, a sharpening disc on said second shaft having peripheral contact with said first mentioned disc, and means for restricting the distance of the movable shaft and disc carried thereon from the other shaft and disc during use, said means including a washer carried on said body member adjacent the periphery of the movable disc, and a base portion adjustably carried on the threaded end of the body member to engage against the washer and force the latter into engagement with the periphery of the movable disc.

2. A tool for sharpening knives and related instruments which comprises a body member, a shaft carried thereon, a pair of sharpening discs mounted on said shaft on opposite sides of said body member, a second shaft carried on said body member movably positioned with respect to said first mentioned shaft, a pair of sharpening discs on said second shaft on opposite sides of said body member, said second discs having peripheral contact with said first mentioned discs, and a base portion carried on said body member for restricting the distance of the movable shaft and disc carried thereon from the other shaft and disc during use.

3. A tool for sharpening knives and related instruments which comprises a body member having a threaded end, a shaft carried on said body member, a sharpening disc mounted on said shaft, a second shaft carried on said body member movably positioned with respect to the said first men-

tioned shaft, a sharpening disc on said second shaft having peripheral contact with said first mentioned disc, and means for restricting the distance of the movable shaft and disc carried thereon from the other shaft and disc during use, said means including an element threaded on the threaded end of the body member adjacent the periphery of the movable disc to engage against said movable disc.

4. A tool for sharpening knives and related instruments which comprises a body member having a threaded end, a shaft carried on said body member, a sharpening disc mounted on said shaft, a second shaft carried on said body member movably positioned with respect to the said first mentioned shaft, a sharpening disc on said second shaft having peripheral contact with said first mentioned disc, and means for restricting the distance of the movable shaft and disc carried thereon from the other shaft and disc during use, said means including a handle threaded on the threaded end of the body member adjacent the periphery of the movable disc to engage against said movable disc.

5. A tool for sharpening knives and related instruments which comprises a body member having a threaded end, a shaft carried on said body member, a sharpening disc mounted on said shaft, a second shaft carried on said body member movably positioned with respect to the said first mentioned shaft, a sharpening disc on said second shaft having peripheral contact with said first mentioned disc, and means for restricting the distance of the movable shaft and disc carried thereon from the other shaft and disc during use, said means including a nut threaded on the threaded end of the body member adjacent the periphery of the movable disc to engage against said movable disc and a handle on the threaded end of the body member.

JOHN GALLO.
